CLAIM

The ornamental design for a record player, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a record player showing our new design;

FIG. 2 is another perspective view thereof;

FIG. 3 is a front elevational view of the player of the record player, shown separately to show aspects of the design that are not visible when combined;

FIG. 4 is a rear elevational view thereof;

FIG. 5 is a left side view thereof;

FIG. 6 is a right side view thereof;

FIG. 7 is a bottom plan view thereof;

FIG. 8 is a perspective view thereof;

FIG. 9 is another perspective view thereof;

FIG. 10 is a front elevational view of one of the speakers of the record player, shown separately to show aspects of the design that are not visible when combined;

FIG. 11 is a rear elevational view thereof;

FIG. 12 is a left side view thereof;

FIG. 13 is a right side view thereof;

FIG. 14 is a top plan view thereof;

FIG. 15 is a bottom plan view thereof;

FIG. 16 is a perspective view thereof; and,

FIG. 17 is another perspective view thereof.

The two speakers shown in FIGS. 1 and 2 are identical, and therefore only a singular speaker is shown in FIGS. 10-17 to clearly show aspects of the design not visible when combined.
